UNITED STATES PATENT OFFICE.

WILLIAM A. CARTER, OF MILWAUKEE, WISCONSIN.

COMPOSITION BUILDING SIDING.

Application filed September 26, 1925. Serial No. 53,842.

This invention relates to composition building sidings, and to the method of making such sidings.

This invention is an improvement over that disclosed in my prior Patent Number 1,532,684, issued to me April 7, 1925, for method of facing wall structures.

In certain types of construction as the brick veneer building, it is the practice to 10 build a frame house with ordinary wooden sheeting and, thereafter, build a brick wall of one brick thickness adjacent the sheeting.

This brick wall is insecurely tied to the sheeting or building, and frequently gives 15 considerable trouble as it easily gets out of alignment due to the settling of the wall. In addition to this, it is not a very secure construction, although materially cheaper than a solid brick wall.

20 This invention is designed to overcome the defects noted above, and objects of the invention are to provide a method of making building sidings and a siding which will simulate either the brick veneer facing or 25 stone block construction or any other desired pattern.

Further objects are to provide a construction such that there is no chance of the 30 formation of cracks in the wall even when settling occurs as the successive slabs are held together in interlocking relation, in addition to the hold secured by the mortar, and in which a very secure and permanent 35 attachment for each slab at a plurality of points to the frame work is afforded in a very simple and novel manner.

An embodiment of the invention is shown 40 in the accompanying drawings, in which:—

Figure 1 is a fragment of a wall showing 45 the slabs in position.

Figure 2 is a transverse sectional view to an enlarged scale of a portion of the wall.

Figure 3 is a sectional view through the mould showing the parts in one stage of 45 construction.

Figure 4 is an edge view of one of the corner blocks or slabs.

Figure 5 is a view of the grading for 50 forming the pattern on the outer face of the slabs.

Figure 6 is an end view of one of the filling members at the points where the slabs are attached to the building wall.

55 Referring particularly to Figure 1, it will be seen that the wall is composed of a

plurality of slabs A which are arranged in a staggered manner so that the joints will be broken by the successive slabs from one tier to the next tier.

This figure shows one side B of an end block and the corresponding side C of the other end of a similar end block, it being understood that these end blocks are made with unequal legs, as will be described in greater detail hereinafter.

In forming the siding, a mould is employed having a bottom portion 1 and end portions 2 and 3. These end portions are provided, respectively with convex and concave portions 4 and 5, which accordingly 60 shape the ends of the slabs along their vertical edges. It is to be understood that the other edges of the slabs, that is, the horizontal edges are flat. Within the mould a plurality of short pins 6 project upwardly 65 from the bottom and serve to position conical corks or filling members 7, as indicated in Figure 3, such filling members or conical blocks, whether of wood or cork, being 70 lightly positioned upon the pins 6 prior to 75 moulding the slabs.

In moulding the slabs, concrete or other material, as indicated at 8, is poured into the mould and smoothed off adjacent the upper ends of the filling members 7. After 80 the filling of the body portion of the mould has been completed and it is properly smoothed off level with the top, a marginal or border member 9' hinged to the body portion, as indicated in Figure 3, is swung 85 downwardly into position and filling material 11 of any suitable color is poured into this portion of the mould. It is then smoothed off and a grating 9, hinged to the marginal or border portion 9', is rocked into 90 position, as shown in Figure 3. The grating is most clearly shown in Figure 3, and is preferably formed of half round rods secured together in any appropriate manner to make the desired pattern whether for 95 brick imitation or imitation of stone or blocks.

It is to be noted that this grating is so formed that when it is rocked into position, it presses a pattern into the filling 100 105 and simulates the joints between successive bricks or blocks. At spaced points in the grating pins are provided, as indicated in Figure 3, and these pins align with the filling member 7 and form apertures in 110

the moulded slab adapted to subsequently receive securing nails hereinafter described and also to indicate the position of the filling member 7 in the finished block.

5 It is to be noted that the grooves formed by the grating may be filled with cement or other suitable material, as indicated at 15, and described subsequently. However, the process may be followed in a slightly 10 different manner. For example, the body of the cement, as indicated at 8, may be one color while the filling 11 may be another color. In pressing the grating 9 into place, this grating may be made to reach to the 15 body portion 8 of the cement, and the channels or grooves formed thereby need not subsequently be filled. Under these conditions the mortar or other material appears to show between successive bricks or blocks and 20 is in reality the uncovered portion of the body part 8 of the cement. This gives an inset joint effect which is so highly desirable in certain types of walls.

Figure 2 shows the manner in which the 25 slabs are applied to the wall. In this figure, the uprights or studdings are indicated at 12, and the sheeting at 13. The slabs are positioned against the sheeting 13 and nails 14 are driven through the apertures left by 30 the pins 10, and through the filling members 7 and into the studding, the heads of the nails being positioned within the appropriate channels left by the grating. These channels are subsequently filled with mortar, 35 as indicated at 15, in order to complete the imitation of brick or stone or concrete construction.

The horizontal joints between successive 40 slabs are also mortared up in the usual manner and the interlocking vertical joints, as indicated at 16, are supplied with a small amount of mortar, and are positioned, as shown in Figure 2. This secures a great 45 amount of rigidity and strength for the wall and prevents the formation of cracks along the wall even when settling occurs. Further, the individual slabs are secured to the wall at a plurality of points, such construction being illustrated in detail in the 50 drawings. In addition to this, the securing means is wholly hidden by the filling 15 for the channels, and thus the securing

means is protected from the action of the weather.

If desired the horizontal joints can also 55 be made lock joints and used with or without mortar.

The corner blocks are formed in the same manner as the slabs previously described and are preferably formed with one of the 60 legs, such as indicated at C in Figures 1 and 4, longer than the other leg B. This secures the staggered arrangement for the slabs A as the corner blocks are turned in alternate directions for successive tiers. 65

It is, of course to be understood that the break between successive slabs may be at any desired points and the corner blocks correspondingly shaped.

It will be seen that slabs have been provided which will imitate any desired fac- 70 ing, and which will freely adapt themselves to the formation of buildings such as the brick veneer buildings or similar types of structures.

Further, it will be seen that a wall con- 75 structed in accordance with this invention is very much more reliable and rigid than can be formed by the ordinary methods.

Although the invention has been described 80 in considerable detail, it is to be understood that the invention may be variously embodied and is, therefore, to be limited only as claimed.

I claim:

An outer slab for a building wall comprising a body portion having its outer face formed with a pattern thereon simulating tiers of distinct members, a series of tapered fibrous blocks embedded in the body portion with their larger ends stopping short of the outer face of the slab and with their inner ends flush with the inner face of the slab, said outer face having depressions formed therein in alignment with said blocks, whereby nails may be driven into the recesses, through the fibrous blocks and into supporting members. 85 90 95

In testimony that I claim the foregoing 100 I have hereunto set my hand at Milwaukee, in the county of Milwaukee and State of Wisconsin.

WILLIAM A. CARTER.
